UNITED STATES PATENT OFFICE

1,970,737

SHEET METAL FENCE POST

Elmer K. Cole, Winterset, Iowa, assignor to Wej-Lock Manufacturing Company, Winterset, Iowa, a corporation of Iowa

Application May 23, 1932, Serial No. 613,078

3 Claims. (Cl. 248—31)

The object of my invention is to provide a simple and inexpensive fence post which may be formed of sheet metal and which may be easily set, and in connection therewith improved means for anchoring guard cables.

More specifically it is the object of my invention to provide in a sheet metal fence post an improved guard cable supporting bracket and means for attaching the same to the post, wherein the said bracket will be positively and firmly connected to the post, and at the same time provide means for strengthening the walls of the post, my improved bracket being particularly adapted to be used in connection with that type of sheet metal posts having one side open.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a perspective view illustrating a sheet metal post and the manner in which my improved cable supporting bracket is attached thereto.

Figure 2 is a detail horizontal sectional view taken through one of the brackets.

Figure 3 is a sectional view taken on the line 3—3 of Figure 2.

Figure 4 is a perspective view illustrating the reinforcing block used in conjunction with anchoring the cable supporting bracket.

Referring to the accompanying drawing, I have used the reference numeral 10 to indicate a fence post formed of a flat piece of sheet metal folded on its longitudinal center to form side members 11. The free edges of the side members are folded inwardly to form back members 12 to form a hollow post of substantially triangular cross section. The members 12 are comparatively narrow so that an opening 13 is provided in the back of the post, said opening permitting the operator to coat the inner surface of the post with paint or other moisture proofing material if so desired. The opening 13 also permits tamping dirt in the lower end of the post at the time it is being set.

My improved cable supporting bracket is preferably formed of cast metal having a body portion 14, one end of which is provided with a transversely arranged opening 15 for receiving the guard cable 16. The opposite end of the bracket 14 is bifurcated to form flanges 17. The inner surfaces of the flanges 17 are designed to fit the outer faces of the wall members 11, in the

manner shown in Figures 1 and 2, with the body 14 supported laterally from the front edge or corner of the post.

Supported within the post opposite each of the brackets 14 I have provided a reinforcing block 18, preferably formed of comparatively thin metal, having its edges provided with an upwardly extending flange 19, said block being designed to fit the inner surfaces of the post in the manner clearly illustrated in Figure 2.

The bottom side of the block is provided with a groove 20 extending from the center of its back edge to the apex end of the block. The bracket 14 is secured in position by means of a bolt 21, one end of which is supported in a screw threaded opening 22 in the inner end of the body 14, said bolt extending through the opening 13 and through a hole 23 in the front edge of the post, the said bolt passing through the groove 20 of the block 18.

By this arrangement it will be seen that the bolt 21 supports the said block 18 against downward movement at the time the said block is placed in position. A washer 24 is supported on the outer end of the bolt for clamping the edges 12 of the post to the back edge of the block 18.

It will readily be seen that after the parts are placed in position, rotation of the bolt 21 will cause the washer 24 to be clamped against the back edge of the block 18, and the inner edges 17 of the member 14 of the bracket to be clamped against the outer faces of the members 11 in such a manner that all of said parts are firmly clamped together. The block 18 reinforces the side walls of the post when the washer 24 and the flanges 17 are clamped in position, and provides a rigid connection between the bracket 14 and the post.

It will readily be seen that any force applied to the bracket will be distributed evenly to the entire surface of the post, in such manner that the bracket cannot be torn loose without destroying the post.

The opening 15 is supported horizontally to receive the guard cables 16, the body 14 being of considerable length to permit the cables 16 to be supported a considerable distance in front of the post, thereby providing means for protecting the post to a certain extent in case the guard cables are struck by a vehicle moving longitudinally of the cable.

The openings 15 are slightly larger than the cable to permit the cable to move freely through the brackets, taking up the tension of the cables.

By threading the cable through openings 110

formed in the bracket, very strong and light means is provided for supporting the cable. Any auxiliary fastening devices such as bolts or rivets are entirely eliminated, thereby eliminating possibility of the connections between the brackets and the cable becoming loose due to vibration of the cable.

I claim as my invention:

- 10 1. A cable support for hollow sheet metal fence posts comprising a body member having one end provided with a longitudinal screw threaded opening and terminating in a bifurcated portion, the other end being provided with a transversely arranged cable receiving opening, a reinforcing block formed to fit the inner surface of a hollow fence post to which the support is attached having its under surface provided with a groove, a washer, a bolt extending through said washer, the groove of said block and into the screw threaded portion of said body.
- 15 2. A cable support for hollow sheet metal fence posts, comprising a reinforcing block having sides tapered toward each other and shaped to fit and engage the inner sides of a post and being formed with a bolt opening, a cable supporting bracket comprising a body portion shaped to fit and engage the outer sides of a fence post and having a cable supporting extension formed with a cable receiving opening at its outer end, said extension being formed with a screw threaded opening at its inner end, and a bolt extended through said reinforcing block and into said screw threaded opening for clamping the fitting sides of the reinforcing block and the said bracket against the adjacent inner and outer surfaces of a post.
- 20 3. A cable support for hollow sheet metal fence posts, comprising a reinforcing block having sides tapered toward each other and shaped to fit and engage the inner sides of a post and being formed with a bolt opening, a cable supporting bracket comprising a body portion shaped to fit and engage the outer sides of a fence post and having a cable supporting extension formed with a cable receiving opening at its outer end, said extension being formed with a screw threaded opening at its inner end, and a bolt extended through said reinforcing block and into said screw threaded opening for clamping the fitting sides of the reinforcing block and the said bracket against the adjacent inner and outer surfaces of a post, and a washer on the bolt of a diameter substantially the same as that of the width of the adjacent side of the reinforcing block for clamping the rear marginal edges of a post against the reinforcing block.

3. A cable support for hollow sheet metal fence posts, comprising a reinforcing block having sides tapered toward each other and shaped to fit and engage the inner sides of a post and being formed with a bolt opening, a cable supporting bracket comprising a body portion shaped to fit and engage the outer sides of a fence post and having a cable supporting extension formed with a cable receiving opening at its outer end, said extension being formed with a screw threaded opening at its inner end, and a bolt extended through said reinforcing block and into said screw threaded opening for clamping the fitting sides of the reinforcing block and the said bracket against the adjacent inner and outer surfaces of a post, and a washer on the bolt of a diameter substantially the same as that of the width of the adjacent side of the reinforcing block for clamping the rear marginal edges of a post against the reinforcing block.
